ATTORNEY

UNITED STATES PATENT OFFICE

EDGAR E. WAYLES, OF EAST HARTFORD, CONNECTICUT

MUFFLER FOR BURNERS

Application filed November 19, 1928. Serial No. 320,298.

My invention relates to that class of burners wherein a number of jets of flame are projected in transverse direction and often in contact with one another, and an object of my invention, among others, is the production of means whereby the noise caused by the intersection of the flames is eliminated.

One form of a device embodying my invention, and in the construction and use of which the objects herein set out, as well as others, may be attained, is illustrated in the accompanying drawings, in which—

Figure 1 is a view in side elevation of a burner embodying my invention with parts broken away to show construction.

Figure 2 is a similar view but looking at a point located at right angles to the point of view of Figure 1.

Figure 3 is a top view of my improved burner.

In the accompanying drawings the numeral 5 indicates the base of my improved burner that may be constructed of any suitable metal preferably cast to shape and having therein a gas chamber 6, with which an inlet pipe 7 communicates, said inlet pipe extending from any suitable source of supply for gas or other combustible fluid.

Such number of burners as may be desired are connected with the base and have passages for flow of gas from the chamber 6 out at the mouth of the burners. In the structure shown herein only two of the burners are shown, but it will be understood that any number of burners that may be desired may be employed and that these burners may be projected in different directions. These burners 8 may be secured to the base as by means of lock nuts 9 in a manner common to structures of this class. The burners 8 are shown as extending in a diagonal direction toward each other so that the flame 10 from each burner is projected transversely across the flame 10 from the opposite burner. In prior structures of this

class these flames are permitted to come into contact with a result that an objectionable roaring noise ensues and it is the object of my present invention to provide means to do away with this noise. This I accomplish by means of a baffle 11 that, in the form shown herein, comprises a plate supported at the end of a shank 12 having a collar 13 fitting a burner tube 8. A set screw 14 may be employed to hold the baffle in place.

The baffle or plate 11 is thus located at about the point at which the flames would intersect and consequently the flames striking the baffle are projected outwardly where they unite into a single flame 15. This flame is sufficient to produce a maximum of heat as for a boiler or similar device, and, at the same time, undue heat is prevented, which undue heat would take place if the flames were permitted to unite.

In accordance with the provisions of the patent statutes I have described the principles of operations of my invention, together with the device which I now consider to represent the best embodiment thereof, but I desire to have it understood that the device shown is only illustrative and that the invention may be carried out by other means and applied to uses other than those above set out.

I claim—

1. A burner including a base having a passage for fluid, a plurality of burners each having a passage communicating with that in the base and relatively inclined to project jets of fuel in intersecting paths, and a baffle located in the intersection of the paths to permit union of the flames outwardly of the baffle.

2. A burner including a base having a passage for fluid, a plurality of burners each having a passage communicating with that in the base and relatively inclined to project jets of fuel in intersecting paths, and a baffle

located between the intersecting paths so that the flames are projected outwardly in parallel united relation.

3. A burner including a base having a chamber, an inlet to said chamber, a plurality of burners each having a passage communicating with said chamber and relatively inclined to project jets of fuel in intersecting paths, and a flat vertical baffle passing through the intersection of said paths so that the flames impinge against the flat faces thereof at an inclined angle and unite above the upper edge thereof.

EDGAR E. WAYLES.
